United States Patent Office.

JOHN MARTINO, JACOB BEESLEY, AND JOHN CURRIE, OF PHILADELPHIA, ASSIGNEES
TO MARCH, SISLER, AND COMPANY, OF LIMERICK STATION, PENNSYLVANIA.

Design No. 3,046, dated May 12, 1868.

DESIGN FOR THE DOORS OF A COOK'S STOVE.

The Schedule referred to in these Letters Patent and making part of the same.

TO ALL WHOM IT MAY CONCERN:

Be it known that we, JOHN MARTINO, JACOB BEESLEY, and JOHN CURRIE, of the city of Philadelphia, in the State of Pennsylvania, have invented or produced a new and original Ornamental Design for the Doors of a Cook's Stove, of which the following is a full, clear, and exact description, reference being had to the accompanying drawings, making a part of this specification, and to the letters of reference marked thereon.

Our invention or production consists in the bas-relief ornamental figures on the respective panels of the side doors and front doors of a cook's stove, as represented in the drawings, A B being one of the oven-doors of the sides of the stove, C D one of the fire-doors of the said sides, and E F one of the front fire-doors; and as the form of the stove is immaterial, the said three doors are grouped together on the same plate in the drawings.

Our design for the "oven" doors consists of the bas-relief ornamental figures *a' b'* on the panel of the same, as shown. Our design for the "side" fire-doors consists of the bas-relief ornamental figures *c' d'* on the panel of the same, as shown; and our design for the "front" fire-doors consists of the bas-relief ornamental figures *e' f'* on the panel of the same, as shown.

What we claim as our invention or production, and desire to secure by Letters Patent, is—

The design for the doors of a cook's stove, as set forth and shown.

JOHN MARTINO,
JACOB BEESLEY,
JOHN CURRIE.
